US00D501794S

(12) **United States Design Patent** (10) Patent No.: **US D501,794 S**
Kunesh et al. (45) Date of Patent: **** Feb. 15, 2005**

(54) **PRESSURE CONTAINER WITH ACTUATOR
OVERCAP**

(75) Inventors: **Edward J. Kunesh**, Franksville, WI (US); **Allen D. Miller**, Racine, WI (US); **Douglas James Birkholz**, Monona, WI (US); **James Charles Boda**, Merrimac, WI (US)

(73) Assignee: **S.C. Johnson & Son, Inc.**, Racine, WI (US)

(**) Term: **14 Years**

(21) Appl. No.: **29/175,997**

(22) Filed: **Feb. 14, 2003**

Related U.S. Application Data

(63) Continuation-in-part of application No. 29/163,027, filed on Jun. 26, 2002, now Pat. No. Des. 470,402.

Primary Examiner—Carol Rademaker**CLAIM**

The ornamental design for a pressure container with actuator overcap, as shown and described.

DESCRIPTION

FIG. 1 is a perspective view of a pressure container with actuator overcap showing our new design;

FIG. 2 is a rear elevational view thereof;

FIG. 3 is a side elevational view thereof;

FIG. 4 is a front elevational view thereof;

FIG. 5 is a top plan view thereof; and,

FIG. 6 is a bottom plan view thereof.

The broken line showing in the drawings is for illustrative purposes only and forms no part of the claimed design.
